UNITED STATES PATENT OFFICE.

ALBERT ENNIS HENDERSON, OF TORONTO, ONTARIO, CANADA.

AIRSHIP.

Application filed May 17, 1917. Serial No. 169,253.

In the use of air-ships both commercially and in offensive and defensive warfare, a number of difficulties, heretofore unsummoned, have been encountered with reference to dirigibles of both the gas bag and aeroplane types. Chief among these difficulties may be mentioned those which render dirigibles ineffective in the proper and accurate aiming and discharge of projectiles whether the object of attack is another dirigible, an observation balloon having more or less movement, a fixed or moving object on land, or a submarine, and of such difficulties, more especially applicable in attack upon a submarine or other moving object may be mentioned the impossibility heretofore of maintaining the offensive or projectile discharging mechanism in a relative state of stability in order to insure accuracy of aim; that of regulating the speed and position of an aeroplane so as to maintain the proper elevation and enable the observers to keep the submarine in sight; that of preventing drift, due to air currents, particularly as to ships embodying the gas bag feature, and that of controlling the position of the air-ship with reference to the object of attack so as to hover or poise thereover either at a regulable speed relative thereto or without progressive movement; that of quickly and effectively changing the elevation or lateral direction of movement or reversal of movement of the air-ship, particularly as regards those of the gas bag type; that of limited load carrying capacity of ships of the aeroplane type, etc., as well as the inconveniences, with reference to gas bag, incident to depending upon ballast as a means of controlling the elevation and the disadvantages in discharging missiles incident to the release of a relatively heavy weight and the consequent recoil or upward displacement of a machine of the gas bag type.

The object of this invention is to overcome or minimize all of these difficulties and disadvantages by providing a ship, especially designed for use in attacking and destroying submerged submarines, wherein the buoyant effect of a gas bag, without dependence upon ballast is combined with the dirigible characteristics of air-planes positioned and adapted for manipulation to provide for elevation and depression, and means for effecting bodily transverse movement of

the supporting element, such as a gas bag, in combination with a stabilized car or supported element adapted for use as an observation and control station or an offensive or ordnance station, from which torpedoes, bombs or other projectiles may be discharged, or both, and also to provide means in connection with such car for assisting in the dirigible control of the ship as a unit.

Further objects and advantages of the invention will appear in the following description of a preferred embodiment, it being understood that changes in the form, proportion and minor details may be resorted to within the scope of the appended claims without departing from the spirit of the invention.

In the drawings,

Figure 1 is a side view partly broken away and shown more or less diagrammatically of an air-ship illustrating one embodiment of the invention.

Fig. 2 is a plan view of the same.

Fig. 3 is an end view.

Fig. 4 is a reversed or bottom plan view of the car or supported element.

Fig. 5 is an end view of the supporting element embodying the gas bag to illustrate more clearly the means which may be located in the auxiliary stations for operating and adjusting the various parts.

Fig. 6 is a longitudinal sectional view of a portion of the supporting element to show the means in the auxiliary station in a plane at right angles to that of Fig. 5.

Fig. 7 is a detail detached view illustrating means which may be employed for operating the air planes of the supported element.

Fig. 8 is a detail view showing the trimming device and means for operating the same.

Fig. 9 is a vertical sectional view in detail of the torpedo mounting and discharging apparatus.

Fig. 10 is a plan view of the cam torpedo releasing element with its support and operating means.

Fig. 11 is a plan view of the upper end of the torpedo seating shell and the clamps carried thereby.

Fig. 12 is a detail bottom plan view of the torpedo head.

Fig. 13 is a detail view of the throw-off

device employed to permit of independent adjustment of the clutches for controlling the movement of the bodily moving propellers.

5. Fig. 14 is a plan view of the same.

Figures 15, 16 and 17 are details of the clutch operating mechanism and the shaft on which it is mounted.

Essentially, the illustrated structure embodies a supporting element 20, a supported element or car 21 and yielding or flexible suspending elements 22 between the supporting and supported elements and consisting, as shown, of cables 23, crosstree 24, 15 cables 25 and springs 26 constituting the main or weight suspending device, and fore and aft cables 27 and 28 having interposed springs 29, all of which parts obviously may be modified in number and position as found necessary or desirable in practice.

As shown the supporting element embodies a gas-bag or like container 30 of the ordinary or any approved compartmental construction equipped with fore and aft propellers 31 and fore and aft rudders 32, the gas bag being of the double ended type, tapered at both extremities so as to provide for longitudinal propulsion in either direction. The propellers may be driven by engines 33 located in observation stations or baskets 34 disposed at equal distances from the extremities of the gas bag, it being the object, not only in this connection, but with reference to other features of the construction, to equalize the weight of the various parts both fore and aft and laterally so as to facilitate the control of the structure and insure the maximum stability under all conditions. Terminal elevating and depressing planes 35 are also provided at both ends of the gas bag, and means, of any preferred or well known construction, may be employed to control their relative position either for simultaneous elevating or depressing action, 40 and thus bodily movement of the structure in the desired direction, or respective elevating and depressing action if necessary in the maneuvering of the machine or as a means of compensating for differential densities of or pockets in the supporting medium.

Located intermediately and spaced uniformly from the extremities of the gas bag are laterally directing air-planes 36 designed to effect, or assist in producing, a bodily transverse or sidewise movement of the gas bag, or to compensate for or modify the effect of transverse air currents, and similarly located at the sides of the gas bag are the elevating and depressing air-planes 37 located, as with reference to the laterally directing air-planes 36, in groups midway of the length of the gas bag so as to maintain the fore and aft equilibrium thereof, said lateral planes and laterally directing planes,

being adjustable as to position by suitable mechanism hereinafter more particularly described, and the former being designed during the forward or rearward progress of the structure to enable the operator to secure a 70 bodily upward or downward movement of the gas bag, or to maintain the same at a predetermined elevation to compensate for any tendency of the gas-bag otherwise to ascend or descend, and thus serve in lieu of 75 ballast in the control of the elevation.

As a means of providing for bodily elevation or depression of the structure whether the latter is progressing longitudinally or is stationary, but more especially under the latter condition, there are provided elevating and depressing fan propellers 38 at equal distances from the extremities of the gas bag and arranged in vertical flues or chambers 39, any suitable means of connection 80 being provided to propel the same in the desired direction as from the engines 33 of the main propellers, as will be explained more in detail hereinafter; while similar propelling fans 40 are arranged in transverse fuses 41 extending from side to side of the gas bag and may also if desired be operated from the same engines, said lateral or transverse propelling fans being arranged in groups 85 or pairs at equal distances from the extremities of the gas bag and being adapted to secure bodily lateral movement thereof. Through the agency of these vertical and lateral revoluble propellers, it is possible to 90 secure a transverse bodily movement of the structure in all directions while the machine is relatively stationary or is making no progress either forward or rearwardly, just as it is possible to secure bodily transverse movement in all directions through the 100 agency of the various air-planes, hereinabove described, when the structure is making headway either forward or aft. The control of the engines and of the positioning means, propellers, rudders, etc., may be effected by operatives located in one or the other of the stations 34, or cooperatively from both stations, or from a central or main station, as hereinafter explained.

The supported element or car of the machine may contain a main pilot station 42, equipped with the necessary apparatus such as a periscope 43 and suitable signalling and operating devices, and especially when the car is provided with an offensive chamber 44 from which torpedoes or bombs 45 or the like are to be discharged, it should be provided with stabilizing means such as a gyroscope 46, so that within the range of the 110 elastic or yielding qualities of the suspending means 22, a uniform horizontal position of the car may be maintained, regardless of the deflection or inclination of the supporting means, so that the operators of the offensive means may be under the necessity of 115 120 125 130

making corrections only for speed of movement, if any, wind velocity and direction, and the like, and without substantial regard to variations in the position of the car 5 due to fluctuations or disturbances of the supporting element. The stabilizing gyroscope may be actuated by any suitable means such as a motor indicated at 46' and as further means of affording propelling power in 10 either direction, motors 47 may be employed to actuate propellers 48, of which any desired number may be provided.

Similarly, auxiliary steering air-planes or 15 rudders 49 may be arranged fore and aft upon the car and at the extremities of lateral wings 50, the car preferably being of what may be termed star-shape to secure a substantial equilibrium fore and aft and laterally, and hence an approximate uniformity 20 of strain upon the suspending means, are arranged elevating and depressing air-planes 51. Also extending laterally from the forward and rearward arms of the car are disposed elevating and depressing air-planes 52 which may be adapted by any 25 suitable or well known means for deflection coincidentally and proportionately to the planes 51 for assistance in maintaining the proper relation between the supporting 30 and supported elements, especially under conditions involving the necessity of speed in movement.

The car may be provided with floats or 35 runners 52' and wheels or rollers 53 for use as in the ordinary practice in landing on water or land.

Before referring more particularly to details of construction and special mechanism, attention is directed to the fact that by reason 40 of the transverse propelling means of the supporting element, not only can the structure be moved bodily either horizontally or vertically, particularly when the ship is not making endwise or longitudinal 45 progress, but it may be moved pivotally by imparting reverse revoluble movement to the fan propellers fore and aft of the center of said supporting element. In other words, the entire structure can be turned on a vertical 50 pivot by the reverse rotation of the propellers 40, located fore and aft of the center of the length of the gas bag, or in case of emergency the same can be up-ended or tilted on a horizontal pivot by reverse rotation 55 of the propellers 38, so as to make it possible almost instantly to change the position of the plane in the required maneuvering thereof. Such operations moreover may be materially assisted by the relative 60 positions of the fore and aft or terminal rudders 32, in horizontal pivotal or swinging movement, and by the fore and aft planes 35 in the vertical pivotal or swinging movement. Also cooperatively therewith, 65 more especially in the horizontal pivotal

movement of the supporting element, the car or supported element may have its fore and aft rudders 49 adjusted to secure a corresponding pivotal movement around a center common with that of the gas bag. Such a 70 possibility of manipulation avoids the necessity of making a broad circumferential swing in order to change the direction of progress of the ship or to initiate a course at a considerable angle from that indicated 75 by the longitudinal axis of the plane while at rest.

The stabilizing of the car or ordnance chamber from which projectiles are to be discharged or dropped in connection with 80 an attack upon a submerged submarine, is secondary only in importance to the characteristics of the projectile and its adaptability to enter and progressively penetrate the water in order to reach its mark, and in 85 this connection, attention is called to Fig. 9 of the drawings wherein there is detailed a form of torpedo designed especially for this purpose, together with the means carried by the car for operating and discharging the same and consisting essentially of a tubular stand or casing 54, registering with a suitable opening in the floor of the ordnance chamber and containing a revoluble shell or seat 55 between which and the stand 90 or casing may be arranged ball or other suitable anti-friction bearings 56, the torpedo 57 being shown seated in said shell or seat and provided with a head 57' arranged removably in a pocket 58 at the top of the shell or 100 seat and held therein by catches 59 which may be yieldingly held in their engaging positions by springs 60 or any equivalent thereof. The shell or seat is provided with a spindle or extension 61 to which may be 105 imparted revoluble movement at any desired velocity, as for example, through means of a pulley 62 and belt 63 driven by a suitable engine or motor, a velocity gauge or speed indicator 64 being connected with the spindle to enable the operator to determine the rapidity of revolution to suit the conditions under which the torpedo is to be released. Exterioly the torpedo is provided with spiral flanges 65 for the purpose 110 of increasing the penetrating power of the torpedo on entering the water and the progressive movement thereof due to the revolution produced by the discharging means, and also to assist in securing accuracy 115 of flight of the torpedo by the gyroscopic movement. Any suitable means may be employed for simultaneously disengaging the catches 60 from the head of the torpedo, such as a cam ring 66, the axial movement 120 of which will repress the tails of all of the catches and withdraw the noses thereof from engagement with the torpedo which is then free to leave the shell or seat under the 125 action of gravity, or other impelling force. 130

It will be understood that the described and illustrated means for manipulating and discharging the torpedo are merely typical of many forms which may be employed in this connection, the essential point being to so discharge or release the missile as to insure a relatively accurate flight and strike the surface of the water with the minimum resistant effect and hence splash, so that the 10 rotatory movement of the projectile may be continued for the purpose of giving the spiral flanges or wings a propelling effect to carry the projectile to its target. Obviously either time or percussion fuses may be employed in this connection and a scale of 15 velocities so far as the speed of rotation of the torpedo at the moment of discharge is concerned may be determined proportionately to the elevation of the point of discharge above the surface of the water to be estimated by experiment and calculation for the guidance of the gunner.

While as hereinabove brought out it is the aim to maintain a normal longitudinal and 20 transverse equilibrium of the supporting element by an equal distribution of the weight fore and aft and lateral, there is a 25 possibility of slight variation, particularly if it should happen that lookouts or operatives located respectively in the auxiliary 30 stations are of different weights, and as a means of compensating for such variations, there is provided a trimming device consisting of a weight 67 located on a suitable 35 track 68 extending longitudinally of the supporting element between the auxiliary stations and adapted to be moved fore or aft as required by any suitable means such as a 40 threaded rod 69 operable from either station by a crank 70.

Many modifications of means for effecting and controlling the movements and operations of the various agencies utilized in the manipulation of the ship and its parts may 45 be devised, but merely for the purpose of illustration, attention is called to Fig. 5 showing an arrangement of parts by which the adjustment of the lateral and laterally 50 directing air-planes of the supporting element may be adjusted, as follows:

The spindles 71 of the side planes may be provided with worm gears 72 with which mesh worms 73 carried by a spindle 74 adapted, as more clearly indicated in Fig. 1, to be actuated from a hand wheel 75, or its equivalent, through the agency of gear connections 76, and similarly the worm shaft or spindle 77 (more clearly shown in Fig. 6) may be turned for the adjustment of the laterally directing planes by means of a hand wheel 78 or its equivalent through the gear connections 79 and spindle 80.

In Fig. 6 there is also shown a conventional form of means for communicating motion from the engine or motor 33 to the

transversely moving propellers 38 and 40, so that either or both may be driven in either direction so as to impart the desired bodily movement to the supporting element. For example, with reference to the propellers 40, an endless belt 81 passing around suitable pulleys 82 and idlers 83 may traverse a driven pulley 84 which by suitable clutch members may be thrown into engagement with either of two shaft elements 85 and 86, the former being actuated directly by the motor and the latter being connected therewith for reverse movement by suitable mechanism such as pulleys 87 on the shaft elements and an endless belt 88 traversing 80 idlers 89. A similar mechanism indicated at 90, and which in view of the foregoing it is unnecessary to describe in detail, may be employed for transmitting motion in either direction through the shaft element 91 to 85 the vertical propeller spindle 92.

In order that either or both fore and aft lateral propellers may be thrown into operative relation with their respective motors for operation either in the same or opposite 90 directions, means for example such as shown in Figs. 5, 6 and 8 may be utilized, the same consisting of an endless cable 93 of wire or the like extended through a suitable casing 94 connecting the auxiliary stations and 95 having a throw-off connection 95 with the clutch shifting levers 96. This endless cable may be arranged to traverse operating pulleys or wheels 97 arranged in the stations, and under normal conditions the turning 100 of either of said wheels will result in throwing both clutches in one direction, whereas by disengaging the lever 96 in one station from the cable, the clutches may be thrown in the reverse direction relatively by the 105 operator in either station so as to secure the desired direction of rotation relatively of the propellers. A similar mechanism may be employed for the control of the fore and aft elevating and depressing propellers. 110 In Figs. 15, 16 and 17, there is shown in detail the shifting lever 96, clutch wheel 84 and shaft element 98 upon which the movable clutch element is feathered.

In Fig. 7 there is illustrated in detail indicated in proper position at 98 in Fig. 1, a device embodying a continuously driven rotary element such as a pulley 99 which may receive its motion from any suitable motor or other source and having its spindle 120 100 provided with a friction pulley 101 adapted to be positioned in contact with either of friction discs 102, 103 carried by worm shaft 104. Said worm shaft is provided with worms 105 meshing with worm gears 106 on the spindles 107 of the elevating and depressing planes 52 of the supported element. It is obvious that the arrangement of the driving disc 101 in contact with one or the other of the friction discs 130

102, 103 will cause the rotation of the worm shaft 104 in one direction or the other to reverse the movements of the air-planes, whereas when said friction disc is in an 5 intermediate or neutral position, the planes will remain stationary and will be held locked by the worms.

This method of operating the planes is merely typical and may be applied to operate 10 those of the supporting element or substituted by means permitting of the turning of the worms manually.

It will also be obvious that the spindle 61 of the torpedo discharging apparatus may 15 be rotated by any suitable mechanism, for example, the belt 63 may be operated by one of the motors housed within the supported element or by a special motor as may be preferred.

20 What I claim is:—

1. An airship having a dirigible supporting element, a car yieldingly supported thereby, means on the car from which projectiles may be released for propulsion by 25 gravity and a gyroscope vertically alined therewith on the car for stabilizing the same, substantially as set forth.

2. An air-ship having a dirigible supporting element including a gas bag, flues 30 extending horizontally therethrough in front and in rear of the center of the length of the gas bag, reversible propelling elements located in said flues, and means for operating the latter in the same or in opposite 35 site directions to effect bodily lateral or pivotal movement of the supporting element.

3. An air-ship having a dirigible supporting element provided with sets of horizontally disposed flues arranged respectively 40 fore and aft of the center of the length of the supporting element, reversible propelling elements mounted in said flues, and means for operating the same simultaneously in the same or in opposite directions.

4. An air-ship having a dirigible supporting element provided fore and aft of the center of its length with groups or transverse horizontal and vertical flues, reversible propelling means located respectively in 50 said flues, and means for operating the same.

5. An air-ship comprising an elongated normally horizontal gas bag, operators' baskets at the front and rear of the bag, and steering means including a set of vertical 55 rudders at front and arranged along the top of the bag and a shaft extending lengthwise of the gas bag connected to said rudders to adjust them simultaneously and connections to said shaft adjacent to each basket, substantially as set forth.

6. An air-ship comprising an elongated gas bag, independent propellers adjacent the opposite ends thereof, a plurality of propellers and rudders arranged in the longitudinal-horizontal axis of said air-ship, inde- 65

pendent motors driving the respective propellers and baskets rigidly secured to the frame work of the gas bag adjacent said propellers, said baskets forming supports for the respective motors and for their operators, substantially as set forth. 70

7. An airship comprising an elongated dirigible gas-bag, oppositely extending propellers at the ends thereof, rudders projecting from each end, transverse horizontal flues at each end, and reversible propellers in said flues, substantially as set forth. 75

8. An airship comprising an elongated normally horizontal dirigible gas bag having oppositely extending propellers at the 80 ends, rudders projecting from each end, vertical and horizontal flues at each end thereof and reversible propellers therein, substantially as set forth.

9. A dirigible airship comprising an elongated cylindrical envelope tapering at the ends, a longitudinal series of rudders on the envelope, radially extending shafts supporting said rudders, and a single shaft extending axially of the envelope, and connections from said shaft to each of said rudders for adjusting said rudders simultaneously, substantially as set forth. 85

10. A dirigible airship comprising an elongated cylindrical envelope tapering at the ends, a longitudinal series of rudders on the envelopes, radially extending shafts supporting said rudders, a shaft extending lengthwise of the envelope and worm gearing connecting said shaft to each of the 90 radially extending shafts, substantially as set forth. 100

11. A dirigible airship comprising a cylindrical envelope, opposed sets of lifting planes normally lying in a horizontal plane passing through the axis of the envelope, and means to move the planes of both sets simultaneously comprising a shaft extending longitudinally of the airship, shafts extending at right angles thereto and connected to the planes, worm gears on the latter shafts and worms on the first shaft engaging said worm gears, substantially as set forth. 105

12. In a dirigible air-ship, an elongated gas container, a longitudinal series of rudders thereon having pivots in a horizontal plane passing through the axis of the gas container, propeller shafts arranged transversely fore and aft of the ship in said plane and propellers thereon co-operating with the 110 rudders to steer the same, substantially as set forth.

13. An airship comprising an elongated gas container, vertical and horizontal flues extending therethrough adjacent to its ends, 115 and propellers in said flues at their intersection with the axis of the gas container, substantially as set forth.

14. In a dirigible airship, an elongated gas container, a longitudinal series of rud- 120

- ders thereon, propeller shafts arranged transversely of the ship and propellers thereon cooperating with the rudders to steer the same laterally, a shaft extending longitudinally of the airship and worm gearing connecting said shaft to each rudder, substantially as set forth.
15. In a dirigible airship, an elongated gas container, a longitudinal series of rudders thereon, propeller shafts arranged transversely of the ship and propellers thereon cooperating with the rudders to steer the same laterally, a shaft extending axially of the gas container and worm gearing connecting said shaft to each rudder, substantially as set forth.
16. In an airship, an elongated gas container, steering means thereon, a car yieldingly supported thereby at a plurality of points along its length, means on the car for leveling it, and means on the car for dropping an elongated bomb with its nose pointing downward, substantially as set forth.
17. In an airship, an elongated gas container, steering means thereon, a car yieldingly supported thereby at a plurality of points along its length, laterally extending planes on the car for bringing it to horizontal position, and means on the car for dropping an elongated bomb with its nose pointing downward, substantially as set forth.
18. An airship comprising a dirigible gas container, and a pilot's cabin, vertical and horizontal shafts passing through the gas container adjacent to the front and rear ends of the same, axially located reversible propellers in the said shafts and, cooperating laterally disposed planes adjustable simultaneously and controlled from the longitudinal center of the pilot's cabin, substantially as set forth.
19. An airship comprising a dirigible gas container, and a pilot's cabin, vertical and horizontal shafts passing through the gas container adjacent to the front and rear ends of the same, axially located reversible propellers in said shafts, cooperating laterally disposed planes adjustable simultaneously and controlled from the longitudinal center of the pilot's cabin, and a yieldingly sup-
- ported separately propelled plane suspended therefrom, substantially as set forth.
20. A dirigible airship having a pilot's cabin and comprising horizontal and vertical shafts located adjacent to the ends thereof and containing reversible propellers at the axial center of the said airship, laterally and vertically disposed planes simultaneously adjustable located at the extremities of the vertical and horizontal axis of said airship, controlling means for the said planes located in the longitudinal axis of the body of the pilot's cabin, and means for cooperated vertical and horizontal action between said planes and the propellers contained within the vertical and horizontal shafts for the purpose of effecting the desired movement of the airship, substantially as set forth.
21. An air-ship comprising a lighter than air supporting element and mechanically operated means located in the line of the vertical and horizontal planes passing approximately through the longitudinal axis of the air-ship for the purpose of effecting bodily lateral, bodily vertical and pivoted operation of the said air-ship, substantially as set forth.
22. An airship comprising a pilot's cabin, a gas container, propelling means therefor, vertical and transverse rudders fore and aft, and a series of horizontal planes controlled from the longitudinal axis of the pilot's cabin said planes being capable of adjustment simultaneously to any desired fixed position for the purpose set forth.
23. An airship comprising a pilot's cabin, a gas container, propelling means therefor, vertical and transverse rudders fore and aft, and series of horizontal planes controlled from the longitudinal axis of the pilot's cabin said planes being capable of adjustment simultaneously to any desired fixed position for the purpose set forth and being located equi-distant fore and aft of the transverse line passing through the center point of the longitudinal axis, substantially as set forth.

ALBERT ENNIS HENDERSON
